UNITED STATES PATENT OFFICE.

CHARLES W. THOMPSON AND FREDERICK A. GREARSON, OF BARRE, VERMONT.

CHISEL.

1,065,407.

Specification of Letters Patent. Patented June 24, 1913.

Application filed October 4, 1912. Serial No. 723,922.

To all whom it may concern:

Be it known that we, CHARLES W. THOMPSON and FREDERICK A. GREARSON, citizens of the United States, residing at Barre, in the 5 county of Washington and State of Vermont, have invented new and useful Improvements in Chisels, of which the following is a specification.

This invention relates to bush hammers or 10 chisels and has for an object to provide a tool of this character wherein the cutting bits will be positively held to the stock by means which will be so constructed that they can be quickly detached from the stock as 15 desired.

In the drawing forming a portion of this application and in which like letters of reference indicate similar parts in the several views:—Figure 1 is a side view of the tool. 20 Fig. 2 is an edge view showing parts in section. Fig. 3 is a section on line 3—3 of Fig. 1. Fig. 4 is a perspective view of the key. Fig. 5 is a perspective view of one of the benches. Fig. 6 is a perspective view of one 25 of the bits.

The tool comprises a shank 1 which is provided at one end with a relatively large substantially rectangular stock or head 2 having its opposite side faces provided 30 with grooves 3 therein to receive the ribs 4 on the companion rocking wedge members 5. These wedge members are of a downwardly decreasing thickness and their outer surfaces have slidably fitted there- 35 against similar wedge members 6. The wedge members 5 are slotted vertically at 7 and the members 6 are slotted in a similar manner as at 7' whereby the members 6 are adapted to slide across the outer surfaces of 40 the members 5. The lower ends of the members 5 extend below the plane of the stock 2 so that they may be brought into flat contact with the outermost bits 8 so as to hold all of the bits positively grouped together. 45 The wedge members 6 are provided below the plane of the members 5 with lugs 9 which bear against the outermost bits 8 whereby when pressure is brought to bear against the tool the resultant tendency will 50 cause the wedge members to automatically coöperate and combine to frictionally, and in wedge like manner engage against the bits to hold them properly associated with the stock of the tool. With a view to hold- 55 ing the bits 8 against lateral relative movements on the cutting end of the stock we

provide the key 10. This key is disposed against the bottom of the stock and its ends extend through the slots 7 in the members 5 and through the similar slots 7' in the wedge members 6. The outer ends of the key 10 are provided with heads 12 which present the relatively broad flat surfaces 13 which extend transversely to the plane of the slots 7' and which are engaged frictionally 60 against the outer surfaces of the members 6. The bits 8 are provided in their upper edges with grooves 14 through which the key 10 extends. Now, from the construction described it is seen that under the force of the cutting bits against the material operated upon the members 5 and 6 will be moved relatively to force their automatic locking engagement against the bits. When it is desired to remove the bits the heads 12 on the 70 key 10 may be struck by a suitable tool and thereby forced against the walls of the grooves 14 and against the walls 15 of the slots 7' to effect release movements of the members 5 and 6 to thereby bring them out 80 of locking contact with the bits as is understood.

In order to provide means by which the wedge members 5 and 6 may be locked against longitudinal movement with respect 85 to each other when in engaging position, we have provided openings 16 in each of said wedge members in alinement with the slots 7 and 7', respectively, therein. We have also provided the stock with recesses 17 in its side faces which are adapted to aline with the openings 16 in the wedge member 6 when they are in their secured engaging position and which are adapted to receive the inbent extremities 18 of a locking member 19 so as 90 to effectively prevent longitudinal movement, or slipping of the wedge members in respect to each other. This locking member is provided with a manipulating or handle portion 20 and is adapted to embrace 100 the wedge members when in its operative position, it being adapted to have its arms 21 expanded when it is desired to draw its inbent locking extremities from engagement with the wedge openings and the stock re- 105 cesses, due to the fact that the said locking member is constructed of resilient material. It is to be further understood that the wedge members 5 and 6 are adapted to be inter- changeable in their positions with relation 110 to the stock and bits, because of the identical construction of both sides of the wedge

members, thus rendering it necessary to provide similar openings in each set of wedge members.

We claim:—

- 5 1. A bush hammer comprising a stock, substantially wedge like members mounted for rocking movement on the sides of the stock and having bit clamping portions disposed below one end of the stock, bits interposed between the members, second wedge members 10 slideable against the first members and having portions engaged against the bits, and a key extending through the wedge members and having flat head portions frictionally bearing against the outer surfaces of the said second members.
- 15 2. A bush hammer comprising a stock, substantially wedge like members mounted for rocking movement on the sides of the stock and having bit clamping portions disposed below one end of the stock, bits interposed between the members, second wedge members 20 slideable against the first members and having portions engaged against the bits, and a key extending through the wedge members and having flat head portions frictionally bearing against the outer surfaces of the said second members.
- 25 3. A bush hammer comprising a stock, substantially wedge members mounted for rocking movements on the stock and having bit clamping portions extending beyond the end of the stock, bits interposed between 30 said portions and provided with grooves therein, a key extending through the grooves in the bits and through the said members, second substantially wedge members slideable against the first members and adapted 35 to force the said first members into locking contact with the bits and having portions below the plane of the first members extending in the direction of the bits and contact-

ing therewith, and flat heads formed on the ends of the key and frictionally bearing 45 against the outer surfaces of the said second members.

4. A bush hammer comprising a stock, substantially wedge-like members mounted for rocking movement on the sides of the stock and having bit clamping portions disposed below one end of the stock, bits interposed between the said members, a second set of wedge members slidably mounted against the first set of members and having 50 bit engaging portions, a key extending through the wedge members and having flat head portions frictionally bearing against the outer surfaces of the said second set of wedge members, and means by which the 55 said second set of members may be locked with respect to the stock when in engaging position.

5. A bush hammer comprising a stock, substantially wedge-like members mounted 65 for rocking movement on the sides of the stock and having bit clamping portions disposed below one end of the stock, bits interposed between the said members, a second set of wedge members slidably mounted 70 against the first set of members and having bit engaging portions, a key extending through the wedge members and having flat head portions frictionally bearing against the outer surfaces of the said second set 75 of wedge members, and detachable means for locking the second set of wedge members in engaging position.

In testimony whereof we affix our signatures in presence of two witnesses.

CHARLES W. THOMPSON.
FREDERICK A. GREARSON.
